UNITED STATES PATENT OFFICE

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A CORPO-
RATION OF NEW JERSEY

FASTENING-INSERTING MACHINE

Application filed February 6, 1929, Serial No. 337,939, and in Great Britain March 1, 1928.

This invention relates to fastening inserting machines and is illustrated herein as embodied in a loose nailing machine.

When inserting fastenings, for example 5 nails, pegs or slugs, by a machine provided with an awl which forms fastening receiving holes in the work pieces presented to the machine, it happens occasionally that the machine fails to insert a fastening in an awl hole. Under such circumstances it is necessary subsequently to drive a fastening into the empty hole. It is an object of the 10 present invention to provide a fastening inserting machine so organized that a fastening can be driven precisely into such an empty hole, or exactly at any other desired point on the surface of a work piece.

With this object in view and in accordance 15 with a feature of the invention, the illustrated machine, which has awl operating means arranged to cause the awl to come to rest out of engagement with the work piece when the machine is stopped and is of the type disclosed in Letters Patent of the 20 United States No. 490,624, granted January 24, 1893, on an application of Louis Goddu, is provided with means by which the awl can be moved into work penetrating position while the machine is at rest so that the awl 25 may act as a work locator. In the illustrated machine the awl operating means includes two members normally held positively together against the action of a spring which, when the two members are released for relative 30 movement, operates to lower the awl to work penetrating position. A manually operated controller is provided, displacement of which may, if desired, not only permit the spring to move the awl to work penetrating 35 position by reason of the disconnecting of two normally connected parts of the awl operating mechanism, but may also be effective positively to move the awl to work penetrating position. When the machine is 40 started, the awl is automatically restored to normal operation.

While, as pointed out above, the invention is illustrated as embodied in a nail inserting machine of the type disclosed in Letters 45 Patent of the United States No. 490,624 it

should be understood that this is simply an example of one of the types of machine in which the invention may be embodied. Obviously it is capable of embodiment in other types of nail inserting machines as well as 55 in machines for inserting fastenings of other kinds.

With the above and other objects in view the invention will now be described with reference to the accompanying drawings and 60 pointed out in the claims.

In the drawings,

Fig. 1 is a front elevation of the head of a fastening inserting machine embodying the 65 invention;

Fig. 2 is a side view, partly in section, of mechanism for temporarily disconnecting by hand the awl of the machine of Fig. 1;

Fig. 3 is a front view of the mechanism of Fig. 2;

Fig. 4 is a plan view of the same; and

Fig. 5 is a side view of a similar mechanism arranged for treadle operation.

The parts of the illustrated machine, other than the awl operating and controlling mechanism, are or may be like the corresponding parts of the machine of Letters Patent of the United States No. 490,624, to which reference may be had for fuller disclosure of the machine than is necessary in the present specification. Thus the machine is provided with a stationary head 10 in which is journaled a main cam shaft 12 carrying at its forward end a lifting cam 14 arranged to cooperate with a lifting block 16 fast on the driver bar 18 of the machine. The driver bar 18 as well as the awl bar 20 of the machine are mounted for approximately vertical reciprocation in suitable ways formed in a swinging head 22 mounted upon the stationary head 10 for 80 swinging movement about the axis of the shaft 12. The machine is also provided with a nail pot or hopper 24 from which nails 28 are fed to a raceway 26 arranged to control the passage of the nails to the driver passage of the throat member 30 of the machine through which reciprocates a driver 32 secured to the lower end of the driver bar 18. At its upper end the driver bar is connected by a link 34 to a lever 36 urged downwardly 95 90 95 100

by a stiff compression spring 38 one end of which engages the lever 36 and the other end of which is secured to a bracket 40 carried by the stationary head 10. As is usual in machines of this type, the rotation of the cam shaft 12 causes the leading end of the raised portion of the lifting cam 14 to engage the lifting block 16 and thereby to lift the driver bar 18 and driver 32 against the compression 5 of the spring 38. When the raised portion of the cam 14 passes out from under the lifting block 16, the spring 38 forces the driver bar 18 and the driver 32 downwardly, at which time the driver passage of the throat member 30 is in alinement with a hole which has been previously formed in the work piece by an awl 42 carried at the lower end of the awl bar 20 and a nail, which has been taken from the raceway 26 by the separator 28, is 10 in the driver passage in front of the driver. 15

The awl 42 is given a four-motion feed, its work feeding and return motion being produced by the motion of the swinging head 22. The vertical movement of the awl bar 20 is transmitted to it from a cam on the shaft 25 12 by mechanism consisting of a cam lever 44, a gear segment 46 (shown in Figs. 1 and 4, but omitted from Figs. 2 and 3) meshing with a rack formed on the awl bar 20, and connections between the lever 44 and the gear segment 46 which will now be described.

In the mechanism shown particularly in Figs. 2, 3 and 4 the lever 44 is provided with a sleeve 47 fixed to the lever and surrounding a shaft 48 carried in suitable bearings in the stationary head 10. A second sleeve 50 is fast upon the shaft 48, adjacent ends of the two sleeves abutting against each other as best shown in Figs. 2 and 4. Both sleeves are 30 restrained against movement lengthwise of the shaft 48. Between the two sleeves 48 and 50 there is a connection comprising a clutch bolt or plunger 52 housed in the sleeve 50 parallel to the shaft 48 and arranged so that one of its ends can enter a socket member 45 54 fixed in the sleeve 48, to which position it is urged by a spring 53. The sleeve 50 has a pin 56 projecting therefrom parallel to the shaft 48 and into an arcuate recess 58 formed 50 in the sleeve 47. In this recess is housed a coil spring 60 one end of which abuts against the pin 56 and the other against one end of the arcuate recess. When the end of the bolt 52 is withdrawn from its socket, as herein- 55 after described, the spring 60 acts to rotate the shaft 48, in a counter-clockwise direction as viewed in Figs. 1 and 3, relatively to the sleeve 47, and thus to lower the awl bar and the awl to work penetrating position.

60 The bolt 52 carries at its outer end a cam member or wedge 62 projecting outwardly from the sleeve 50. Pivoted to the stationary head 10, adjacent to the shaft 48, is a controller which in the construction of Figs. 2, 3 and 4 takes the form of a hand lever 64. The

lever 64 is provided with a surface 65 arranged to contact, when the lever is pulled to the right as shown in Fig. 3, with a cam surface 63 formed on the wedge piece 62 and by pressure against the wedge piece causes the bolt 52 to be moved to the left as viewed in Fig. 2 and thus to be withdrawn from the socket 54. After the bolt 52 has been fully withdrawn the hand lever 64 may be moved still further, then pressing against a portion 75 66 (Fig. 4) of the wedge piece 62 which is parallel to and below the shaft 48. Such further movement of the hand lever 64 aids the spring 60 in causing the shaft 48, the sleeve 50 and the gear segment 46 to rock, and in fact provides positive means to lower the awl 42 to its work penetrating position.

As shown in Fig. 2 the end of the bolt 52 is slightly tapered and the socket in which it fits is of a similar form. Such an arrangement facilitates the entrance of the end of the bolt into the socket and is usually sufficiently positive to drive the awl. However, as an additional safeguard the sleeve 47 is provided with a lug 68 (Fig. 3) which abuts 85 during the normal operation of the machine against a face 70 formed on the sleeve 50 and is separated therefrom only by manual depression of the awl.

In the construction shown in Fig. 5 the awl may be lowered when the machine is at rest by the rocking of a bell-crank lever 80 fulcrumed at 82 to the stationary head 10 and bearing at one end against a lug 84 projecting from a locking bolt 86, which in this construction is housed in a sleeve 88 fixed to the lever 44 and is spring pressed into a socket 90 carried by a sleeve 92 fast upon the shaft 48. The lever 80 may be rocked by a treadle to which it is connected through a treadle rod 94 so that the depression of the treadle will force the bolt 86 out of the socket 90 and will cause the power stored in the spring 60 to lower the awl. This treadle may be the treadle by which the horn 96 of the machine is lowered. Thus the lowering of the horn of a fastening inserting machine equipped as illustrated in Fig. 5 will be effective to lower the awl of the machine and the lowered awl may conveniently be used as locating means by which the exact position of the insertion of the first fastener in the work piece next presented to the machine may be determined.

Referring now particularly to a machine equipped as shown in Figs. 1 to 4, if it is desired to lower the awl while the machine is at rest so that a work piece may be properly presented for the insertion of the nail in an empty awl hole, it is only necessary for the operator to move the hand lever 64 to the right as viewed in Figs. 1 and 3. The hand lever 64 thus engages the cam surface 63 formed on the wedge piece 62 of the bolt 52, carrying the bolt 52 to the left as viewed in Fig. 2 and withdrawing its end from the

socket 54 against the compression of the spring 53. The spring 60, aided if desired by continued pressure of the hand lever 64 against the bolt 52, rocks the sleeve 50 and the gear segment 46 in a counter-clockwise direction as shown in Figs. 1 and 3, thus lowering the awl bar 20 and the awl 42. The operator then positions the work piece in such manner that the awl 42 is located in the empty hole or 10 at any other point on the surface of the work piece where it is desired to insert a nail or the first nail of a series. Upon starting the machine the lever 44 and the sleeve 48 will be rocked, compressing the spring 60 and bringing the socket 54 into alignment with the end of the bolt 52 which is accordingly snapped into the socket by the spring 53, and the machine operates in its normal manner 15 through one or more cycles until brought to rest by the releasing of its clutch treadle.

Having described my invention, what I claim as new and desire to secure by Letters Patent of the United States is:

1. A fastening inserting machine having, 25 in combination, an awl, means for operating the awl to cause the awl to penetrate a work piece presented to the machine to form fastening receiving holes therein, said means being arranged to cause the awl to come to rest 30 out of engagement with the work piece when the machine is stopped, and means constructed and arranged to move the awl into work penetrating position while the machine is at rest to cause the awl to act as a work locator 35 and arranged also to restore the awl to normal operation when the machine is again started.

2. A machine according to claim 1 in which the awl is connected to its operating means 40 by a clutch device constructed and arranged to be unclutched to permit the awl to be moved while its actuating means is at rest and to be reclutched automatically upon the starting of the machine thereby to restore the awl to normal operation.

3. A fastening inserting machine having in combination an awl, means for causing the awl to penetrate a work piece presented to the machine and to be withdrawn therefrom, 50 arranged to cause the awl to come to rest out of engagement with the work piece when the machine is stopped, and means operable when the machine is at rest to cause the awl to move to its work penetrating position.

55 4. A fastening inserting machine having, in combination, an awl, means for causing the awl to penetrate a work piece presented to the machine and to be withdrawn therefrom arranged to cause the awl to come to rest out of engagement with the work piece when the machine is stopped, and manually controlled power operated means operable when the machine is at rest to cause the awl to move to its work penetrating position.

60 5. A fastening inserting machine having

an awl operable to make fastening receiving holes in a work piece presented thereto and arranged to come to rest with the awl withdrawn from the work piece, and a manually operable controller arranged, when displaced from its normal position with the machine at rest, to cause movement of the awl to its work penetrating position.

6. A fastening inserting machine having an awl operable to make fastening receiving holes in a work piece presented thereto and arranged to come to rest with the awl withdrawn from the work piece, a manually operable controller arranged, when displaced from its normal condition with the machine at rest, to cause movement of the awl to its work penetrating position, and means constructed and arranged to restore the awl to normal operation on restarting the machine.

7. A fastening inserting machine having an awl arranged to penetrate a work piece presented to the machine to form fastening receiving holes therein and arranged also to feed the work piece to fastening inserting position, a hand lever arranged to be displaced while the machine is at rest, and means operated by displacement of the hand lever to move the awl to work penetrating position.

8. A fastening inserting machine having an awl arranged to penetrate a work piece presented to the machine to form fastening receiving holes therein and arranged also to feed the work piece to fastening inserting position, a manually operable controller arranged to be displaced while the machine is at rest, a spring tending to move the awl to work penetrating position but normally restrained against such action, and means operated by displacement of the controller to permit the spring to move the awl to work penetrating position.

9. A fastening inserting machine having, in combination, an awl, means for causing the awl to penetrate a work piece presented to the machine, then to move transversely of its work penetrating movement to feed the work piece to fastening inserting position, then to withdraw from the work piece and finally to return to its initial position, which position it occupies when the machine is standing at rest, and a hand lever operable when the machine is at rest to cause the awl to move to its work penetrating position.

10. A fastening inserting machine having an awl arranged to penetrate a work piece presented to the machine to form fastening receiving holes therein and arranged also to feed the work piece to fastening inserting position, a manually displaceable controller arranged to be displaced while the machine is at rest, means operated by displacement of the controller to move the awl to work penetrating position, and means arranged to restore the awl to normal operation on restart.

ing the machine after displacement of the controller.

11. A fastening inserting machine having an awl arranged to penetrate a work piece presented to the machine to form fastening receiving holes therein and arranged also to feed the work piece to fastening inserting position, a manually operable controller arranged to be displaced while the machine is at rest, a spring tending to move the awl to work penetrating position, a latch normally restraining such action of the spring connections between the controller and the spring arranged to cause displacement of the controller to release the latch thereby permitting the spring to move the awl to work penetrating position, and means arranged to restore the awl to normal operation on restarting the machine.

12. A fastening inserting machine having, in combination, an awl, means for causing the awl to penetrate a work piece presented to the machine and to be withdrawn therefrom and arranged to cause the awl to come to rest out of engagement with the work piece when the machine is stopped, a driver constructed and arranged to drive fastenings into the holes formed by the awl in the work piece, and means operable when the machine is at rest to cause the awl to move to its work penetrating position.

13. A fastening inserting machine having an awl constructed and arranged to make fastening receiving holes in a work piece presented thereto and arranged to come to rest with the awl withdrawn from the work piece, a driver arranged to drive fastenings into the holes formed by the awl on the work piece, and a manually operable controller arranged when displaced from its normal position with the machine at rest to cause movement of the awl to its work penetrating position.

14. A fastening inserting machine having an awl, means for operating the awl to form fastening receiving holes in a work piece presented thereto and arranged to cause the machine to come to rest with the awl withdrawn from the work piece, a driver, means for operating the driver to insert fastenings in the holes formed by the awl in the work piece, a manually operable controller arranged when displaced from its normal position with the machine at rest to cause movement of the awl to its work penetrating position, and means constructed and arranged to restore the awl to normal position when the machine is again started.

15. A fastening inserting machine having an awl arranged to penetrate a work piece presented to the machine to form fastening receiving holes therein and arranged also to feed the work piece to fastening inserting position, a driver, means for operating the driver to insert fastenings in the holes formed

by the awl in the work piece, a manually operable controller displaceable while the machine is at rest, means operated by displacement of the controller to move the awl to its work penetrating position, and means for restoring the awl to normal operation on restarting the machine after displacement of the controller.

16. A fastening inserting machine having, in combination, two members mounted end to end for rotation about a single axis and each provided with a projecting lug, a plunger carried by one of the members, a spring tending to hold the plunger with its end in a socket carried by the other member thereby holding the two lugs in engagement with each other, means tending to cause relative rotation of the two members in a direction to separate the two lugs but restrained against such action by the plunger when its end is in the socket, an awl and an awl bar connected to one of the members, a cam, a cam lever rocked by rotation of the cam and connected with the other member thereby causing rotation of the cam to reciprocate the awl, and a manually operable controller by displacement of which the plunger may be withdrawn from the socket when the machine is at rest thereby permitting relative rotation of the two members and moving the awl to work penetrating position.

17. A fastening inserting machine having, in combination, two sleeves mounted end to end for rotation about a single axis and each provided with a projecting lug, a plunger carried by one of the sleeves, a spring tending to hold the plunger with its end in a socket carried by the other sleeve thereby holding the two lugs in engagement with each other, a spring tending to cause relative rotation of the two sleeves in a direction to separate the two lugs but restrained against such action by the plunger when its end is in the socket, an awl and an awl bar connected to one of the sleeves and arranged for reciprocation by rocking of said sleeve, a cam, a cam lever rocked by rotation of the cam and connected with the other sleeve thereby causing rotation of the cam to reciprocate the awl, and a manually operable controller by displacement of which the plunger may be withdrawn from the socket when the machine is at rest, thereby causing relative rotation of the two sleeves under the action of their spring and moving the awl to work penetrating position.

18. A fastening inserting machine having, in combination, two sleeves mounted end to end for rotation about a single axis and each provided with a projecting lug, a plunger carried by one of the sleeves and formed with a cam surface, a spring tending to hold the plunger with its end in a socket carried by the other sleeve thereby holding the two lugs in engagement with each other, a spring tend-

ing to cause relative rotation of the two sleeves in a direction to separate the two lugs but restrained against such action by the plunger when its end is in the socket, an awl and awl bar connected to the plunger-carrying sleeve and arranged for reciprocation by rocking of said sleeve, a cam, a cam lever rocked by rotation of the cam and connected with the other sleeve thereby causing rotation of the cam to reciprocate the awl, and a hand lever provided with a surface formed and arranged by displacement of the hand lever to engage the cam surface of the plunger to withdraw the plunger from its socket, thereby disconnecting the two sleeves, and by further displacement of the hand lever after the plunger has been withdrawn from its socket positively to rock the plunger-carrying sleeve thereby moving the awl into work penetrating position.

In testimony whereof I have signed my name to this specification.

WILLIAM THOMAS BUCKINGHAM ROBERTS.
